QUICK-FIRING CORONA REGULATOR TUBE

Herbert Friedman, Arlington, Va.

Application November 24, 1954, Serial No. 471,130

3 Claims. (Cl. 313—197)

(Granted under Title 35, U. S. Code (1952), sec. 266)

The invention described herein may be manufactured and used by or for the Government of the United States of America for governmental purposes without the payment of any royalties thereon or therefor.

The present invention relates to a quick-firing corona regulator tube and is particularly an improvement over my Patent No. 2,523,287 for Voltage Regulator.

In the art of corona voltage regulation by means of a diode type regulator tube of the character disclosed in my above identified patent, there exists a statistical delay in the initiation of a corona discharge following the application of an overvoltage to the tube. This delay comes about by virtue of the fact that the initiation of the corona discharge depends upon the occurrence of a fortuitous external ionizing event. As a consequence, the corona firing or starting voltage is unreliable. In certain applications where delicate instruments rely on the voltage output for the regulator, this initial overvoltage may obtain magnitudes which are detrimental to the life or even instantly destructive of the instruments.

The present invention overcomes the foregoing shortcomings by providing the regulator tube with a simple, convenient, self-contained ionizing mechanism. Specifically, the instant invention includes the addition of an auxiliary electrode disposed within the tube and structurally proportioned and positioned relative to the main cathode so as to undergo a discharge at applied voltages below that for which main electrode structure operates. The auxiliary electrode discharge operates, as hereinafter described, to provide an ionizing effect on the electrode structure to minimize the delay time in the tube and thus to stabilize the corona starting voltage for the tube. The provision of an auxiliary electrode in the tube not only is a simple and convenient way of overcoming the aforementioned shortcomings but also has many advantages over other prior tubes that required radio-active material to excite the gas and cause ionization. The tube of the present invention can be made much cheaper, does not require special handling during manufacture and use to avoid contamination due to radio-active radiation, can be disposed of readily, and does not require the expensive materials required in the other tubes.

It is accordingly an object of the present invention to provide a simple, reliable correction for the foregoing shortcomings in corona regulator tubes.

A further object of this invention is to provide a simple, inexpensive corona regulator tube having stabilized starting voltage properties.

A still further object of this invention is to provide a corona regulator tube having the foregoing advantages and yet which is safe to handle at all times without danger of contamination from radiation.

Other and more specific objects of this invention will become apparent upon a careful consideration of the following detailed description when taken together with the accompanying drawings, in which:

Fig. 1 is a simplified elevational view of an exemplary embodiment of the invention,

2

Fig. 2 illustrates, in circuit form, a type of circuit useable in practicing the teaching of this invention, and

Fig. 3 shows a graph illustrating the applied voltage V vs the growth of corona discharge in the tube.

5 Referring now to Fig. 1 there is illustrated a side elevational view of one typical embodiment of the regulator tube 10 comprising this invention. As exemplified, the tube may comprise a vessel or envelope 14 made of any desired material, such as glass, in which three electrodes are disposed. These electrodes include a cathode cylinder 11 made from any suitable metal such as stainless steel, copper, etc., held in position by a support 21 through the side of the envelope 14 which has a reinforced portion 22 on the side thereof. The support 21 also affords an electrical connection for the cathode 11. An inner coaxial anode cylinder 12, also made of any suitable material and having the same ratio of radius relationship to the cathode cylinder as disclosed in Patent No. 2,523,287, and a corona stabilizing auxiliary electrode 13 illustrated as being disposed externally of the cathode cylinder 11. The auxiliary electrode 13, which may assume various shapes, may also be made of any desirable metal and may be placed within the cathode cylinder instead of externally thereof, if desired. In the 10 illustrated embodiment, the electrode 13 consists of a fine wire spaced externally of and near the cathode cylinder. In a typical tube the electrode 13 may be approximately $\frac{1}{3}$ the diameter of the anode and spaced a distance from the cathode equal to approximately $\frac{1}{3}$ the anode distance from the cathode surface. As indicated by the above dimensions, the radius of curvature of the wire electrode 13 and/or its spacing relative to the main cathode 11 is chosen so that when electrode 13 is electrically paralleled with the main anode by a suitable resistance R_2 as shown in Fig. 2, a corona discharge between electrode 13 and cathode 11 will take place at a voltage below that required to initiate a corona discharge between the main electrodes 11 and 12. The 15 cathode cylinder is preferably equipped with an aperture 16, or a slit, or some form of an opening therein located adjacent the electrode 13 so that the ultraviolet light produced by the corona discharge between electrode 13 and the cathode can shine through the opening to cause photoelectric emission from the cathode to ionize the 20 gas within the cathode cylinder. Although it is not necessary that there be an opening through the cathode cylinder, it is a preferred arrangement when the electrode 13 is external of the cathode cylinder.

As indicated, the three electrodes are preferably enclosed within a gas tight vessel or envelope, which in turn is filled to a predetermined pressure with any suitable gas such as helium, neon, mixtures of rare gases with hydrogen, etc., as disclosed in Patent No. 2,523,287. The electrodes are connected to terminal pins which 25 are well known in the art.

In the circuit illustrated in Fig. 2, the positive or unregulated high voltage (+H. V.) is applied to the circuit as shown and the regulated voltage is obtained from across the main electrodes 12 and 11 of the tube. The 30 circuit resistance R_1 connected in series with the anode 12 provides the necessary voltage dropping resistance in the typical regulator fashion. Resistance R_2 connected in the circuit before the resistance R_1 as shown at A and in series with the electrode 13, or alternatively the resistance R_2 can be connected between the resistance R_1 and the anode as indicated at B operates to electrically isolate the auxiliary electrode from the main discharge path.

Fig. 3 shows in graphical form the manner in which 35 the corona discharge current for the main electrodes of the tube varies with applied voltage. The discharge portion above V_{min} is known as the region of "stable corona

discharge." Specifically, this region is defined as that portion of the voltage-current characteristic where a self-sustaining discharge occurs. The region between V_s and V_{min} is known as the unstable corona region. When the positive high voltage is applied, the tubes of the type disclosed in my above identified patent have a tendency to fire at any point above V_{min} in the stable corona region, the specific point depending upon the occurrence of a fortuitous, external ionizing event. The object of this invention is to stabilize the firing level at a point near V_s . In the prior tube, at voltages lower than V_{min} the discharge is not self-sustaining and breaks off after a mean lifetime that approaches zero, as the applied voltage approaches V_s . If ionizing radiation is supplied from an external source, or if the cathode is illuminated by ultraviolet light the initiation of corona can be stabilized down to V_s . Below V_s no corona discharge is possible. Thus when the discharge electrode 13 which is proportioned and positioned relative to cathode 12 to undergo a stable corona discharge at a voltage below V_s fires, the attendant ultraviolet light shines on the cathode, and ionizing radiation is supplied to the main electrode structure. The threshold voltage for the establishment of stabilized corona in the auxiliary discharge is, as hereinabove mentioned, set at a value slightly below the threshold V_s for unstable corona in the main discharge. The exact voltage level at which stable corona is made to occur in the auxiliary discharge is thought to be immaterial so long as the ultraviolet light produced by the auxiliary electrode 13 shines on the cathode ionizing the gas within the tube and thereby allowing the main electrodes to fire in a stabilized corona discharge region without any delay.

Obviously many modifications and variations of the present invention are possible in the light of the above teaching. It is therefore to be understood, that within the scope of the appended claims, the invention may be practiced otherwise than as specifically described.

What is claimed is:

1. In a corona voltage regulator tube comprising a 40 gas filling, a hollow cylindrical cathode, a wire anode dis-

posed centrally along and in said cathode, the improvement which comprises an auxiliary fine wire anode having a diameter substantially less than that of said anode in said cathode, said auxiliary fine wire anode being so spaced from and arranged in respect to said cathode as to undergo corona discharge at voltages below the corona discharge potential of the wire anode in said cathode.

2. In a corona voltage regulator tube comprising a gas filling, a hollow cylindrical cathode, a wire anode disposed centrally along and in said cathode, the improvement which comprises an aperture in the wall of said cathode, an auxiliary fine wire anode externally of said cathode and having a diameter substantially less than that of said anode in said cathode, said auxiliary fine wire anode having a portion thereof lying within the zone opposite said aperture in the wall of said cathode and so spaced from and arranged in respect to said cathode as to undergo corona discharge at voltages below the corona discharge potential of the wire anode in said cathode.

3. In a corona voltage regulator tube comprising a gas filling, a hollow cylindrical cathode, a wire anode disposed centrally along and in said cathode, the improvement which comprises an aperture in the wall of said cathode, an auxiliary fine wire anode externally of said cathode and having a diameter equal to about one-third the diameter of said anode in said cathode, said auxiliary fine wire anode having a portion thereof lying within the zone opposite said aperture in the wall of said cathode and so spaced from and arranged in respect to said cathode as to undergo corona discharge at voltages below the corona discharge potential of the wire anode in said cathode.
